LIGHTNING ARRESTER.

Application filed October 14, 1924. Serial No. 743,549.

Our invention relates to protective devices and it has particular relation to lightning arresters of an inclosed type employed in modern electrical power distribution systems.

Practical experience has shown that in order to insure continuity of service and preserve the apparatus connected to the overhead transmission lines principally employed in the distribution of power, every distribution transformer scattered upon the system should be protected by a lightning arrester disposed adjacent to the transformer. The question as to whether it is desirable to leave the system unprotected or to employ a large number of lightning arresters disposed on the tops of the poles near the transformers is purely a matter of economy and depends upon the comparative cost of the interruptions in the continuity of the operation and in the exchange of the damaged transformers and upon the cost of the lightning arresters themselves.

Modern lightning arresters of the distribution-line type, such as the autovalve arresters, for instance, are so designed as to require practically no attention during many years of service under normal operating conditions. For practical reasons, the arrester is usually inclosed in a strong porcelain casing to safeguard the same against the influence of the weather and against accidental damage through rough handling and, in its outer appearance, the arrester very closely resembles an insulator. In the course of service, it happens, however, that through abnormal operating conditions, such as in the case when a high-voltage line comes into contact with a low-voltage line, an arrester may be damaged to such extent that it cannot clear the line upon the termination of the disturbance, and the distribution system to which the arrester is connected would thereupon continue to send current through the arrester.

In some cases, especially in systems of large capacity, sufficient power will flow into the arrester to cause the same to break with a more or less explosive action. In many systems, however, there is not sufficient power to bring about the destruction of the arrester in a short time and the dangerous state of continuous arcing in the interior of the arrester may continue for an

unreasonably long time. By reason of its rugged construction, the arrester often remains externally intact, thus giving an appearance of perfect operativeness, when, as a matter of fact, the apparatus to which the arrester is connected is without protection. Considerable trouble and expense is involved in locating the arresters that have failed.

The foregoing conditions make the cost of inspection and maintenance of a large number of scattered arresters out of proportion to the cost of their initial installation. A serious obstacle is thus imposed on the maintenance of efficient lightning-arrester protection in modern distribution systems.

One object of our invention is to provide a distribution lightning arrester combining all the properties of rugged construction met with in modern lightning arresters, with means for securing a positive destruction of the arrester upon internal damage to the same.

Another object of our invention is to provide a lightning arrester of the above-described character producing a visual indication upon failure of the same.

Still another object of our invention is to provide a protective device of the above-described character that will quickly clear the line even under conditions where the power available for the destruction of the same is relatively small.

The foregoing and other objects of our invention will best be understood by reference to the accompanying drawing, wherein

Figure 1 is a view in vertical section illustrating a lightning arrester embodying our invention,

Figs. 2, 3 and 4 are views similar to Fig. 1 illustrating modifications of our invention, and

Figs. 5 and 6 are elevational views illustrating a lightning arrester embodying our invention as mounted upon a pole, before and after failure of the arrester.

Referring to Fig. 1, a lightning arrester comprises a porcelain casing 1 resembling an insulator in external appearance. The upper end of the casing constitutes a cylindrical chamber 2 enclosing a plurality of resistor members 3 constituting a discharge path for abnormal surges on the system to be protected. The arrester shown in the

drawing is of the type known as the auto-valve arrester, the principles of which are disclosed in the copending application of Joseph Slepian, Serial No. 535,810, filed 5 February 11, 1922, patented September 23, 1924 No. 1,509,493, and assigned to the Westinghouse Electric & Manufacturing Company. The novel principles of our invention are, however, equally applicable to 10 arresters of other types.

The resistor members 3 are of disk shape and may be separated by mica spacers 5, thereby providing a plurality of minute gap devices assembled in a substantially vertical column. A series insulating gap device 6 is placed on the top of the disk column, the disks and an insulating gap device being held in place by means of a spring member 7 pressing the same against a base member 8 which closes the bottom of the chamber 2. A high-voltage lead 11 extends into the upper portion of the arrester and a ground lead 13 extends up through a centrally disposed opening in the base 8 into 25 the lower portion of the chamber. The leads are in electrical contact with terminal plates 14 and 15 at the upper and the lower ends of the discharge path of the arrester. The top of the arrester is inclosed by means 30 of a porcelain cap 16 which is secured to the porcelain casing 1 by means of an insulating gum poured into the space between the cap and the casing. The arrester is supported by a clamp 17 surrounding the porcelain casing.

The principal novel feature of our arrester is a special construction of the porcelain casing which renders the same critical with respect to abnormal heating caused 40 by a continuous current flowing through the arrester. According to our invention, abnormal heat generation in the arrester causes the base portion 8 of the arrester and the ground lead 13 to break off from the casing, thereby stopping the discharge 45 through the arrester and producing a visual indication of its failure.

In carrying out our invention, we make the base portion 8 of the chamber 2 of relatively 50 low heat capacity as compared with the remainder of the porcelain casing. The base member 8 is disposed in an intermediate position between the upper and lower ends of the casing 1 and it is joined with the main body of the casing 1 by an integral tubular portion 21 of restricted cross section. The tubular portion 21 is so disposed that the expansion of the base member 8, attendant upon heating the same, 55 brings the relatively weak tubular section 21 into bending or shearing stress and causes the same to crack.

In operation, when the arrester is damaged and fails to clear from the line, the 60 current passing through the arrester gen-

erates heat. The heat is generated principally in the stack of resistor disks 3 and the heat flows along the path of best heat conduction toward the base member 8, increasing its temperature at a time when the 70 temperature of the main body of the casing 1 is still relatively low on account of the poor thermal connection between the disks 3 and the walls of the chamber 2. As the base member 8 expands, the stress upon the 75 weak tubular section 21 increases until it breaks off. The base member 8 and the ground lead 13 drop out from the arrester under the action of their own weight and the weight of the members constituting the 80 discharge path in the arrester, augmented by the action of the spring member 7.

By the utilization of the construction shown in the drawing, it is possible to secure a positive break in the portion joining 85 the base member 8 to the casing, with relatively slight energy input into the arrester without materially affecting the ruggedness 90 of the arrester structure, since the weak tubular section 21 and the base member 8 are protected by the overhanging bottom portion of the casing which thus serves as a protective skirt of sufficient mechanical strength to withstand the shocks and blows 95 encountered in shipment and in rough handling during installation.

In addition to the preferred embodiment of our invention shown in Fig. 1, the same may be applied in different modifications. In Fig. 2, for instance, is shown a construction wherein the inner chamber 25 of the porcelain casing 26 has its bottom 27 connected to the side walls by a cylindrical extension 28 of somewhat smaller diameter than the main portion of the chamber. The 105 diameter of the extension 28 is smaller than the discs 29 in order to prevent the same from falling out of the chamber when the bottom member 27 breaks off the casing 100 upon abnormal heating.

In order to provide a contact between the bottom terminal plate 31 of the ground lead 32 and the high-resistance disks 29, a filler 33, such as a metal disk, having good electrical and thermal conductivity, is disposed in the space between the thermal plate 31 and the high-resistance disks. The height of the filler 33 is somewhat greater than the height of the extension 28 in order to bring the bottom member 27 and the terminal plate 31 under the action of the spring member disposed within the upper portion of the arrester. Such construction prevents the disks and other loose members disposed within the chamber of the arrester from dropping out of the same when the bottom member 27 breaks off from the arrester.

In Fig. 3 is shown a modification of the structure shown in Fig. 1 wherein the tubular section joining the base member 8 to the 130

main body of the casing is avoided and the breakage of the base member is obtained by providing merely a restricted section 35 at the joint of the base member and the main body of the casing 36. This construction is less effective than the preferred arrangement shown in Fig. 1.

In Fig. 4 is shown a modification of our invention wherein the bottom of the chamber 41 of the porcelain casing 42 is inclosed by a metallic plate 43, such as brass. The metallic plate inclosing the bottom of the casing may also constitute the lower terminal of the discharge path of the arrester. The bottom plate 43 is held at the edges by a thin-walled tubular extension 45 of the main body of the casing. The plate 43 is clamped tightly between the walls of the extension or may be joined thereto by cement, for instance.

Upon abnormal operation of the arrester, the heat generated initially raises the temperature of the bottom plate 43 and the expansion of the bottom plate breaks the extension 45 off from the body of the casing 42. The broken off portion of the casing, together with the bottom plate 43, drops down, interrupting the circuit of the arrester and producing a visual sign of its failure.

The mounting of our improved arrester is shown in Figs. 5 and 6. The arrester is secured to a cross arm mounted upon a pole carrying the line conductors and the distribution transformer. The high-potential lead 11 of the arrester is connected to the line and the ground lead 13 is connected to the ground.

Fig. 6 shows the arrester after failure with the bottom of the arrester chamber hanging downward upon the ground lead 13. The fact that the ground lead drops off from the arrester and hangs down prevents any accidental damage that might occur in case the high potential lead should fall off from the arrester.

Our invention is susceptible of various modifications not shown in the drawing and we desire that the language of the appended claims shall cover all such modifications.

50 We claim as our invention:

1. A double-walled casing comprising an outer wall portion having sufficient mechanical strength to withstand shocks incident to shipment and handling, and having a substantially cylindrical bore, an inner cylindrical wall member of reduced thickness joined at its inner end to an intermediate portion of the bore of said outer wall portion, said inner cylindrical wall member being capable of withstanding relatively great steady pressures applied in an axial direction but being easily subject to fracture as a result of radially applied pressures, and an end wall portion joined to the free end of said inner cylindrical wall member and capable of ap-

plying a breaking stress in a radial direction as a result of abnormal heating.

2. The combination with a device which may, at times, become overheated, of a casing therefor having a substantially cylindrical bore and end closure portions, the casing having a cylindrical wall portion adjacent to one end closure portion having relatively great strength in an axial direction but being easily subject to fracture as a result of radially applied pressures, the end closure portion adjacent to said cylindrical wall portion being in good thermal connection with the source of heat in said device, whereby said end closure portion may be readily heated to break said cylindrical wall portion by laterally applied stresses, the remaining portions of said casing being in relatively poor thermal connection with the source of heat in said device whereby they are not subjected to any substantial stresses resulting from unequal heating.

3. A lightning arrester comprising a double-walled insulating casing having an outer wall portion having sufficient mechanical strength to withstand shocks incident to shipment and handling, and having an interior bore, an inner cylindrical wall member of reduced thickness joined at its inner end to an intermediate portion of the interior bore of said outer wall portion, said inner cylindrical wall member being capable of withstanding relatively great steady pressures applied in an axial direction but being easily subject to fracture as a result of radially applied pressures, and an end wall portion joined to the free end of said inner cylindrical wall member and capable of applying a breaking stress in a radial direction as a result of abnormal heating, a column of active lightning-arrester material disposed within said casing in good thermal connection to said end wall portion, a flexible ground lead connected at the end of said column which rests on said end wall portion, and a high-potential lead entering the casing adjacent to the other end thereof.

4. The combination with a columnar shaped lightning-arrester device, of a casing therefor having a substantially cylindrical bore and end closure portions, the casing having a cylindrical wall portion adjacent to one end closure portion having relatively great strength in an axial direction but being easily subject to fracture as a result of radially applied pressures, the end closure portion adjacent to said cylindrical wall portion being in good thermal connection with the source of heat in said device whereby said end closure portion may be readily heated to break said cylindrical wall portion by laterally applied stresses, the remaining portions of said casing being in relatively poor thermal connection with the source of heat in said de-

vice whereby they are not subjected to any substantial stresses resulting from unequal heating.

5. A lightning arrester comprising a double-walled insulating casing having an outer substantially cylindrical portion of sufficient mechanical strength to withstand shocks incident to shipment and handling, an inner cylindrical wall member of reduced thickness joined at its inner end to an intermediate portion of the interior bore of said outer cylindrical portion, said inner cylindrical wall member being capable of withstanding relatively great steady pressures applied in an axial direction but being easily subject to fracture as a result of radially or laterally applied pressures, and an end wall portion joined to the free end of said inner cylindrical wall member and capable of applying a breaking stress in a radial direction as a result of abnormal heating, a column of active lightning-arrester material disposed within said casing in good thermal connection to said end wall portion, said end wall portion having a central opening therein, a flexible ground lead extending through said opening, a terminal plate engaged to said ground lead and disposed between said end wall and said column, spring tension means at the other end of said column and operative to expel said terminal plate and ground lead upon the fracture of said inner cylindrical wall member, said terminal plate having a smaller diameter than said column, and a shoulder provided within the internal bore of said

casing and operative after the expulsion of the terminal plate to prevent the expulsion of said column from the casing.

6. A lightning arrester comprising a vertically disposed cylindrical casing of insulating material, a high-potential lead entering the upper portion of said casing, a column of active material disposed within said casing, a flexible ground lead suspended from the bottom of the arrester, and means disposed underneath said column and operating upon the occurrence of abnormal heating of said column to permit said ground lead to fall clear of the arrester while retaining said column within said casing, the upper portions of said casing remaining intact.

7. A lightning arrester comprising a vertically disposed cylindrical casing of insulating material, a high-potential lead entering the upper portion of said casing, a column of active material disposed within said casing, a flexible ground lead suspended from the bottom of the arrester, spring tension means pressing downwardly against the top of said column, means operating upon the occurrence of abnormal heating of said column to permit said ground lead to be expelled from the casing, and means operative after the expulsion of the ground lead to prevent the expulsion of said column from said casing.

In testimony whereof, we have hereunto subscribed our names this 10th day of October, 1924.

LAWRENCE R. GOLLADAY.
IRVING R. SMITH.
